5 Claims. (Cl. 62—42)

This invention relates to an arrangement for cold insulation in technical large-scale apparatus for methods of gas liquefaction and/or gas separation to be carried out at low temperatures. The invention uses primarily those temperature ranges which are below the condensation temperature of nitrogen. At atmospheric pressure this is 77.4° K., hence the invention concerns primarily insulation arrangements for sheathing parts operating at temperatures below approximately 80° K.

The invention concerns mainly apparatus which contains liquid hydrogen or similar cold liquids, such as liquid helium, neon or mixtures thereof.

On a laboratory scale, the cold insulation heretofore was generally effected by arranging the apparatus in a vacuum—particularly a high vacuum. In industrial plants which exceed laboratory scale it is difficult to produce a jacket that surrounds the entire plant which seals vacuum-tight on all sides. With dimensions of about 4 to 5 m. height and width respectively the expenditure for obtaining a satisfactory vacuum and a vacuum-tight jacket respectively presents considerable difficulties. The difficulties increase if a simple cylindrical form of the jacket is abandoned—in order to save material—in favor of a shape that tapers to the top or bottom.

Known modes for solving this insulation problem consist in surrounding a low-temperature plant working with liquid hydrogen with two different fitted cylindrical jackets. Such proposals have become known particularly for a gas decomposing plant for separating deuterium from liquid hydrogen. The lower part of the rectifying column arrangement proper together with the other parts working at the above-mentioned low temperatures is surrounded by a cylindrical jacket which is sealed moisture-proof on all sides and filled on the inside with gaseous hydrogen. The upper part of the rectifying column arrangement is conducted at the top through the cover of this cylindrical jacket and surrounded with a second cylinder of a smaller diameter, which second cylinder is attached on the insulating jacket underneath. The upper cylinder is sealed vacuum-tight and evacuated on the inside. This arrangement has the great disadvantage, however, that considerable heat conduction and consequently cold losses appear in the butt joint of the jackets.

The difficulty underlying the problem is that it is not possible to use nitrogen as an insulating atmosphere at these low temperatures. Insulation with hydrogen alone is not sufficient, however, particularly for the colder parts of the rectifying column. For this reason this part of the known plant was also provided with a vacuum jacket.

The object of the invention is to find a different solution for the insulation problem, where a butt joint between two different adjacent insulation jackets is to be avoided under any circumstances.

In order to maintain the temperatures and temperature differences required for the invention, a special elaboration of the idea of the invention provides for the housing of the different pieces of apparatus in two separate insulated chambers with different temperatures. These two insu-

2

lated chambers are formed by two insulating casings one inside the other, which together enclose the most important—preferably all—of the pieces of apparatus of the plant which function at temperatures below the condensation temperature of nitrogen, and the outer casing encloses at least a few and preferably all of the remaining pieces of apparatus functioning at higher temperatures, although in certain cases these may still be lower than 273° K., the inner casing being filled with gaseous hydrogen and the outer casing with gaseous nitrogen.

For actual cold insulation, each casing is filled in the conventional manner with the usual insulating materials, such as slag wool, glass wool, spun materials from polymerization products, as, for instance, polystyrene, asbestos or similar substances, in some cases at least partially in powder form.

Instead of the gases mentioned above—hydrogen and nitrogen—other gases or mixtures of gases can also be used, which do not condense at the temperatures prevailing in the interstices of the insulating material. Thus at least the inner casing may contain, for instance, instead of or as well as hydrogen, helium, neon or a similar gas, or a mixture of any two or more of these. Where the inner and the outer casings contain different gases, it is an essential condition that the gaseous fillings of the inner and outer casings do not together form an explosive mixture. Thus for instance, in the absence of hydrogen in the inner casing, air or another gaseous mixture containing oxygen can be used in the outer casing.

To insure that the gaseous atmosphere in the two casings is maintained, the inner casing, in accordance with a special elaboration of the idea of the invention, is constructed of a cold resistant material, for example cold resistant metal, such as aluminum or a suitable steel, such as V2A steel or a tempered steel, or copper, and is welded wherever necessary in such a way as to be gas-tight.

The necessary apertures for communication between the two casings are made with turned and/or ground flanges into which the closing pieces are very closely fitted. On the outer casing the closures are at least fitted with rubber sealing joints in the conventional manner.

In a further elaboration of the invention, a pressure slightly higher than that in the outer casing is produced in the inner casing, in order to prevent the entry of condensable gas in the event of the inner chamber not being quite gas-tight. In order to maintain this excess pressure, the pressure in the inner chamber and in the outer chamber is regulated. As in the inner casing at least—and to a certain degree also in the outer casing—there is a vertical temperature gradient, at least when there is a fractionating column in the center, for instance for the purpose of deuterium extraction, the difference of pressure between the inner and the outer casing varies at different heights. The excess pressure must therefore be regulated so that at every point in the inner chamber the prevailing pressure is greater than that in the outer chamber. The pressure in the outer chamber may conveniently be kept slightly above atmospheric pressure. In the example described in which the inner filling is hydrogen and the outer filling nitrogen, a pressure difference of about 50–300 kg./m.² (water column) between the inner and outer pressure and about 100–200 kg./m.² (water column) between the outer pressure and atmospheric pressure obtains.

Each casing is equipped in suitable places, for instance at the top and at the bottom, with one inlet or outlet orifice for regulating the pressure. The simultaneous adjustment of inlet and outlet produces a certain direction of flow. This can be chosen as required, so that it either follows the direction of the pressure drop in the casing concerned, or runs contrary to it.

The replacement of the quantities of gas necessary to compensate for losses can be effected either as required or at a fixed rate, in some cases continuously. In the latter case a certain permanent through stream is maintained.

In the drawing, one version of the heat insulation in accordance with the invention is diagrammatically shown as an example.

In the single figure of drawing, a fractionating column for separating deuterium from liquid hydrogen is shown at 1, the fractionating column being surrounded by two spaced casings 2 and 3, one fitted over the other. Both are cylindrical in their top and bottom parts, with an intermediate, tapering portion roughly in the middle. In the two insulating chambers thus formed, various other auxiliary pieces of apparatus are installed, of which an accessory column 4 in the inner chamber and in the outer chamber the regenerators 5 are indicated diagrammatically. Each chamber is packed with slag wool. In the inner chamber is gaseous hydrogen with a pressure p_i ; in the outer chamber is gaseous, pure nitrogen with a pressure p_a . If p_o designates the pressure of the surrounding air atmosphere, then the condition $p_i > p_a > p_o$ should be fulfilled. For the maintenance of the required pressure, the entrances to the insulation chambers are fitted with automatic or hand-operated pressure reducing valves 6 and 7, whereas overflow valves 8 and 9 are fitted in the outlets. The hydrogen flows in at the top through 6 and flows out at the bottom through 9, while the nitrogen flows in at the bottom 7 and flows out at the top through 8.

The inner insulation chamber rests on a heat insulating foundation 10, which is sealed off below by a metal plate 11 which is welded into the casing 2, so that the inner insulation chamber is completely encased on all sides.

The outer insulation chamber could actually also be constructed in the same way. However, in the example given it is sufficient for the metal plate 11 to be large enough to cover the base of the outer insulation chamber at the same time, as well the outer casing being attached to it at the bottom by means of a flange. The whole construction stands in the conventional manner on a concrete foundation 12 in which a heat insulating layer of masonry 13 is inserted in the immediate vicinity of the insulation structure in order to reduce the heat gradient.

The outer casing 3 is constructed in the conventional manner and is made of copper, V2A steel or a tempered, cold-resistant steel.

The inner casing is made of aluminum or also of a tempered, cold-resistant steel, and is composed of several cylindrical elements. The separate elements are assembled on the site and welded together. The welded seams must subsequently be subjected to an expansion treatment.

Before being welded together the separate cylindrical elements are assembled and screwed together by means of suitable flanges 14 and 14', 15 and 15', etc. Finally the various joints, the vertical ones as well as the horizontal annular joints, are covered over on the outside with strips or rings 16, 17, etc., of a material of particularly high notch impact strength at low temperatures, such as above all copper, which may have suitable corrugation in order to enable them to give way in the face of stresses occurring due to the various cooling temperatures of the casing 2. The edges of sheet metal strips 16, 17, etc., are welded onto the surrounding parts of the casing. As the covering strips fixed on are relatively thin in comparison to the thickness of the casing, their assembly is particularly simple and free of tension.

This application is a division of applicant's co-pending application Serial No. 831,679, filed August 4, 1959, now Patent No. 3,107,992.

I claim:

1. Means for the thermal insulation of plants consisting of several apparatus parts operating at different tempera-

tures including temperatures below the condensation temperature of nitrogen, which comprises at least two spaced insulating casings disposed one over the other, the casings being packed with insulating material, both casings together enclosing the apparatus parts operating at the lowest temperature in the plant, the outer casing alone enclosing other apparatus parts operating at higher temperatures though still below 0° C., the inner casing containing a gaseous medium having a boiling point at least no higher than that of the gas operating in the apparatus, the outer casing containing a gaseous medium with a poor heat conduction and a higher boiling point than that of the gas being contained in the inner casing.

2. Means for the thermal insulation of plants consisting of several apparatus parts operating at different temperatures including temperatures below the condensation temperature of nitrogen, which comprises at least two insulating casings disposed one over the other, the casings being packed with insulating material, both casings together enclosing the apparatus parts operating at the lowest temperature in the plant, the outer casing alone enclosing other apparatus parts operating at higher temperatures though still below 0° C., the inner casing containing a gaseous medium with a boiling point at least not higher than that of the gas operating in the apparatus, the gas contained in the inner casing and the gas operating in the apparatus not being explosive if mixed, the outer casing containing a gaseous medium which is a poor conductor of the heat and is not explosive when mixed with the gas contained in the inner casing.

3. Means for the cold insulating of plants consisting of several apparatus parts operating at different temperatures, preferably where temperatures are below the condensation temperature of nitrogen, which comprises at least two insulating casings disposed one over the other, the casings being packed with insulating material, both casings together enclosing the apparatus parts operating at the lowest temperature in the plant, the outer casing alone enclosing other apparatus parts operating at higher temperatures though still below 0° C., the inner casing containing a gaseous medium under a higher pressure than that of the surrounding atmosphere and having a boiling point at least no higher than that of the gas operating in the apparatus, the outer casing containing a gaseous medium which is a poor conductor of heat and being present at a pressure between the pressure of the gas contained in the inner casing and the pressure of the surrounding atmosphere.

4. Means for the cold insulating of plants consisting of several apparatus parts operating at different temperatures, preferably where temperatures are below the condensation temperature of nitrogen, which comprises at least two insulating casings disposed one over the other, the casings being packed with insulating material, both casings together enclosing the apparatus parts operating at the lowest temperature in the plant, the outer casing alone enclosing other apparatus parts operating at higher temperatures though still below 0° C., the inner casing containing the same gas as the gas operating in the apparatus, the outer casing containing nitrogen in the gaseous state.

5. Means for the cold insulating of plants consisting of several apparatus parts operating at different temperatures, preferably where temperatures are below the condensation temperature of nitrogen, which comprises at least two insulating casings disposed one over the other, the casings being packed with insulating material, both casings together enclosing the apparatus parts operating at the lowest temperature in the plant, these apparatus parts standing on a heat insulating base, the base being set on a metal plate which seals the inner casing, the metal plate being underpinned with heat-insulating masonry material, the outer casing likewise being sealed by means of said metal plate and alone enclosing other apparatus parts operating at higher temperatures though still be-

low 0° C., the inner casing containing a gaseous medium having a boiling point at least no higher than that of the gas operating in the apparatus, the outer casing containing a gaseous medium which is a poor conductor of heat, the inner casing having at the highest point therein a conduit and at the lowest point a valved outlet line to regulate the pressure in the inner casing, the outer casing having at the lowest point a conduit and at the highest point a valved outlet line to regulate the pressure in the outer casing.
